UNITED STATES PATENT OFFICE.

NIELS ANTON CHRISTENSEN, OF MILWAUKEE, WISCONSIN.

FLUID-COMPRESSOR.

No. 823,156.

Specification of Letters Patent.

Patented June 12, 1906.

Original application filed September 9, 1899, Serial No. 729,957. Divided and this application filed December 11, 1899.
Serial No. 739,900.

To all whors it may concern:

Be it known that I, NIELS ANTON CHRISTENSEN, residing at Milwaukee, in the county of Milwaukee and State of Wisconsin, have 5 invented certain new and useful Improvements in Fluid-Compressors, of which the following is a specification, the within application being divisional of an application filed by me on September 9, 1899, Serial No. 10 729,957, for a high-pressure fluid-compressor.

My invention relates to fluid-compressors generally, and more particularly to the cooling arrangement therefor, whereby the compressed air may be cooled before its admission 15 and delivery into the reservoir.

While for convenience I have herein shown my invention as applied to a high-pressure fluid-compressor for obtaining extremely high pressures, in which type of compressor 20 my cooling arrangement is particularly useful, yet it will be understood that my invention is applicable to fluid-compressors generally.

In the drawings, Figure 1 is an elevation of 25 a compressor having a plurality of compression-cylinders and operated by a motor mounted on the compressor; Fig. 2, a sectional plan on line 2 of Fig. 3; Fig. 3, a section on line 3 of Fig. 1; Fig. 4, a sectional elevation on line 4 of Fig. 3, and Fig. 5 a section on line 5 of Fig. 4.

My invention is shown applied to a compressor having a plurality of compression-cylinders, and I will proceed to describe such 35 invention in this connection without intending to limit myself to any number of cylinders.

The main frame or compressor-casing 1 has a chamber 2, in which the main shaft 3 and other working parts of the compressor 40 operate. The main shaft extends extraneous of the casing and is provided at one end with a large gear (not shown) contained within the gear-casing 4: This gear meshes with a pinion (not shown) contained 45 within a casing 5. This pinion is mounted on the armature-shaft 6 of the electric motor 7, whose base 8 preferably forms the top cover of the compressor-casing, thereby closing the chamber 2 and protecting the working parts contained therein. Obviously any 50 other source of power may be employed to drive the main shaft.

Fig. 1 represents a compressor having three compression-cylinders, and as all of the cylinders and parts operating therein are similar

in construction and operation a description of one of them, such as illustrated in Fig. 3, will suffice for all. The three cylinders are arranged in a forward extension 9 and communicate with the chamber 2, so that such 60 chamber may be filled with water, oil, or other lubricant for lubricating the pistons. Each cylinder 10 has a single-acting piston 11 with a crank connection with the main axle 3. The forward end of the cylinders is provided with a head or cover 12, containing the discharge-port governed by a discharge-valve 13 and controlling a passage 14, passing through the head or cover and leading to the reservoir indirectly through the cooling devices 65 hereinafter referred to. Each cylinder is provided with a separate suction-valve 15 of any suitable construction. Each discharge-passage 14 extends downward through the head or cover, where it has a nozzle 16, 70 to which is secured, by means of the coupling 17, a gooseneck 18 underneath the extended part of the main casing and communicating with a cooling-coil 19, preferably of copper, located in a rectangular chamber 20, which is 75 formed in the compression-base or casing below the chamber 2 by means of the false bottom or partition 21. The forward end of the cooling-chamber is closed by three covers or plates 22, which are separate and independent, for a purpose hereinafter stated. There is thus provided a cover or plate for 80 each cylinder and coil, which plates are bolted or otherwise secured to the casing or pump-base. As clearly shown in Fig. 5, the gooseneck and the inlet end 23 of the copper coil are brazed or otherwise secured to the plate 22 and communicate with each other through a 85 passage 25 in the boss or enlargement 26, formed on the plate. The outlet end 27 of 90 the coil is also secured to the plate and communicates with the branch discharge pipe or passage 28, leading to a discharge-pipe 29, which is common to all of the discharge-passages of the different cylinders.

The common discharge-pipe 29, as shown in the drawings, discharges on the right, and the other end is closed by a cap 30; but obviously this cap may be changed to the opposite end and the compressed air taken off 105 from the left-hand end, as desired. The head or cover 9 is hollow, having internal passages and open-work 31 for the free circulation of water which enters through the inlet 32, as shown in Fig. 1. By means of the circula- 110

tion of water through the head or cover the discharge-valves and the end of the cylinder are cooled. The water also circulates from the back head into a jacket 33 and also into 5 the chamber 20 in the pump-base containing the cooling-coils, from which the water passes through an outlet 34. The head or cover is bolted or otherwise secured to the pump-base or compressor-casing by means of a series of 10 bolts 35, extending into the chamber 2 and having nuts 36 therein. Smaller cap-screws 37 may be used, passing through the head and screwing into said base.

The air compressed in the cylinders is 15 charged through passages 14, through the gooseneck 18, through the coils 19, through the branch pipe 28, and finally to the common discharge-pipe 29, from whence it is delivered to any suitable reservoir. By means 20 of the cooling arrangement shown the air which is heated to a high temperature, especially when compressed to a high degree, becomes cooled by the circulating water, which serves not only to keep the parts of the 25 compressor as cool as possible, but also serves to cool the discharged air before it has been delivered to the reservoir. With the metal parts constructed of the proper character of material having high tensile strength and 30 good conductivity, so as to radiate the heat away to this body of circulating water as fast as it is created by the compressor, I am enabled to provide a compressor which is capable of compressing to a very high degree, even 35 in one stage. Furthermore, the arrangement shown is not only simple, but compact, and provides a compressor having a minimum of parts and a minimum of material consistent with the necessary strength required 40 for obtaining the high pressures.

The fluid delivered through the delivery pipe or passage is highly heated by the heat of compression, and to provide for the expansion the connection between the discharge- 45 nozzle and the cooling-coil is what is known as a "gooseneck," which will receive expansion without cracking or loosening of joints or connections. While the fluid in such connection may be highly heated, it becomes 50 thoroughly cooled in the coil, and, as I have found in practice, the common discharge-pipe leading to the reservoir or place of use is comparatively cold. Moreover, the cooling-chamber serves to cool the lubricant employed in the piston-chamber, which is directly above the cooling-chamber.

It is obvious that any one or more of the compressors may be cut out of operation by closing suitable valves communicating with 60 the common discharge-pipe. After disconnecting the branch pipe 28 from the cover 22 and uncoupling the gooseneck from the discharge-nozzle 16 and unbolting the cover the entire cooling-coil may be withdrawn for any 65 purpose without disturbing the operation of

the other compressors. Of course when any one of the compressors is taken out of operation the discharge-valve 13 is removed, so that this particular compressor will work without compression.

70

My compressor as above constructed and operated is capable of meeting all conditions to which an apparatus of this character could be subjected. Moreover, the entire device is compact and light in construction 75 and the parts easy of examination and repair without stoppage of all the compression-cylinders.

75

Although I have described more or less precise forms and details of construction, I 80 do not intend to be understood as limiting myself thereto, as I contemplate changes in form, the proportion of parts, and the substitution of equivalents as circumstances may suggest or render expedient and without departing from the spirit of my invention.

85

I claim—

1. A compressor comprising a casing, a plurality of cylinders therein having pistons, such casing having a false bottom forming a 90 cooling-chamber integral with said casing and each of said cylinders having independent and valve-governed suction and discharge passages, a series of independently-removable covers for said chambers provided with passages for the inlet and exit of the fluid under pressure, and independent cooling-coils located in said cooling-chamber and connected at their ends with said passages in the removable covers.

95

2. A compressor comprising a casing, a plurality of cylinders therein having pistons, such casing having a false bottom forming a cooling-chamber integral with said casing, each of said cylinders having independent and valve-governed suction and discharge 105 passages, a series of independently-removable covers for said chamber, independent cooling-coils located in said cooling-chamber and connected at their ends with the covers 110 respectively, a discharge-pipe common to all of said discharge-passages and coils, and independently-operable cut-out valves located 115 between the coils and discharge-pipes.

100

3. A compressor comprising a casing, a plurality of cylinders therein having pistons, such casing having a false bottom forming a cooling-chamber integral with said casing, means for operating the pistons, each cylinder having independent and valve-governed 120 suction and discharge passages, independent cooling-coils one for each discharge-passage and located in said chamber, independent covers for said chamber, to which covers the coils are secured at their free ends and with 125 which they are bodily removed, a common discharge-pipe having communication with said discharge-passages and coils and independent cut-off valves located between the coils and common discharge-pipe.

115

120

125

130

4. In a compressor, the combination with a compressor-casing having a false bottom forming a cooling-chamber, a plurality of cylinders located in the casing and having pistons for compressing and discharging fluid therefrom, a series of independent cooling-coils located in the cooling-chamber, a series of gooseneck connections between the coils and the discharge from the cylinders, and a series of independently-valve-governed delivery-pipes communicating with said coils for delivering the fluid under pressure after the same has passed through such coils. 45
5. In a compressor, the combination with a compressor-casing having a false bottom forming a cooling-chamber, a plurality of cylinders located in the casing and having pistons for compressing and discharging fluid therefrom, a series of independent cooling-coils located in the cooling-chamber, a series of gooseneck connections between the coils and the discharge from the cylinder, a series of independently-valve-governed delivery-pipes communicating with said coils for delivering the fluid under pressure after the same has passed through such coils, said gooseneck connections being detachable from said cylinders, and a delivery-pipe common to all of said series of delivery-pipes leading 50
- 20 from the coils. 55
6. In a compressor, the combination with a compressor-casing having a false bottom forming a cooling-chamber, a plurality of cylinders located in the casing and having pistons for compressing and discharging fluid therefrom, a series of independent cooling-coils located in the cooling-chamber, a series of gooseneck connections between the coils and the discharge from the cylinders, a series 50
- 25 of independently-valve-governed delivery-pipes communicating with said coils for delivering the fluid under pressure after the same has passed through such coils, said cylinders having delivery-pipes terminating in nozzles, a series of removable closures for closing the front of said cooling-chamber and provided with inlet and outlet passages, said cooling-coils being located in such chamber and secured at their ends in and communicating with said passages in the closures and 75
- 30 being bodily removable with their respective closures, a series of goosenecks forming expandible connections between said nozzles and said inlet-passages in the closure, and a series of independently-valve-governed delivery-pipes communicating with the outlet-passages in said closures. 80
